INSULATOR STRUCTURE

Lory B. Stewart, Falconer, N. Y.; Marian Marguerite Stewart and William F. Stewart, executors of estate of Lory B. Stewart, deceased, assignors of one-third to Karl L. Thielscher, Buffalo, N. Y.

Application August 16, 1938, Serial No. 225,238

5 Claims. (Cl. 174—154)

This invention relates to an insulator structure and to one which is especially adapted for use as a three-way insulator bracket on buildings for telephone or other wiring, and it aims generally to provide an improved, inexpensive, efficient and durable construction enabling attachment of the wiring for anchoring, guiding or dead ending, and which is unitary for use where a plurality of insulators or insulating brackets, usually specifically different in construction, are now necessary in a like situation.

The invention further has for objects, to provide an article or structure of the present character which is interlinked with the wiring so as to retain the latter should the insulation break and consisting of parts which are thereafter separable to facilitate release of the wiring incidental to the replacement of the insulator structure and to provide an article wherein the insulator is formed as connected spools having ribs providing wire-receiving grooves, with the ribs of different spools connected for reinforcement, and, further, to provide such a construction as has screw means or the equivalent enabling attachment of the article at any desired angle, even to brick or stone buildings, according to the disposition of the co-acting wiring.

Various additional objects and advantages will become apparent from a consideration of the description following, taken in connection with the accompanying drawing illustrating operative embodiments.

In said drawing:

Figure 1 is a view in elevation of an insulator article constructed in accordance with the invention;

Figure 2 is an end view of the article of Figure 1;

Figure 3 is a side elevation of the article of Figure 1;

Figure 4 is a view in longitudinal section, through a slightly modified form of an insulator article and structure to which it is attached;

Figure 5 is a perspective view of a plate and band as used in the construction of Figure 4; and,

Figure 6 is a longitudinal section through another modified form.

Referring specifically to the drawing, wherein like reference characters designate like or similar parts, and first to Figures 1 to 4, 10 designates a body of suitable insulating material, such as glass, porcelain, synthetic resin, or any equivalent, which is molded while in a plastic condition and permitted to solidify and harden in the shape illustrated. Such body consists of a base portion 11,

preferably having a flat surface 12 for direct engagement with the attaching structure, which may be a brick, stone, or the like, as at 13. In addition to base 11, said body 10 has parallel spools 14 and a spool 15 disposed at a right angle 5 thereto, the spools being connected by integral webs 16. Such base and spools produce a central opening 17 therebetween through which telephone or other electric wiring is passed, and which is anchored to or guided by the spools, being engaged specifically in grooves 18 thereof intervening ribs 19. It will be noted that adjacent ribs 19 of the spools 14 and 15 are integrally connected in right angular relation, as shown in Figure 2, to afford maximum reinforcement. 10 15

Embedded in the body 10 in parallelism to the surface 12 is a plate 20, of brass, or any other suitable metal. Also, embedded in the body 10 and jointly with said plate 20 are one or more arch shaped elements 21, of brass, or any other suitable 20 metal.

Said elements 21 are shown in Figures 1 to 3, and are preferably in the form of wires and employed in pluralities, joined, if desired, at their apices by tie wires 22. At their terminals, elements 21 pass through openings 23 adjacent corners of the plate 20. The connection in the openings 23 is separable or detachable initially, so that upon fracture or in the absence of the body 10, the telephone or other wires will be retained thereby. To this end, the terminals of the wires 21 are coiled, as at 24, to the remainder of the wires. 30 35

Attached to the plate 20 at an opening 25 therein, accessible through a bore 26 in the body 10 extending from surface 12 to the opening 17, is 35 an attaching screw 27. Such screw has a screw threaded portion 28 passing through opening 25 and secured detachably but rigidly to the plate 20 by nuts 29 on opposite sides thereof. The bore 26 affords clearance for the application of special 40 wrenches or tools to apply the said nuts 29. After the nuts 29 are applied and the screw or detachable member 27 thus secured in place, said bore is preferably filled with a cementitious material or other insulating compound 30. 45

The free or distal end 31 of screw 27 may be finished as a lag screw or in any other preferred manner, according to the material of the building element 13 or the like to which it is adapted to be fastened. Element 13 may specifically be 50 a brick, stone, or the like, having a hole 32 drilled therein and containing a dowel shield structure 33 (Fig. 4) therein to facilitate anchorage of the screw at any desired angle or position. It will also be realized, that the hole 32 may be pro- 55

vided in a joint between bricks, or stones, or even provided in a concrete or like wall.

Figures 4 and 5 specifically show the use of a single metallic tie or arch element which functions like that at 21, and which is here designated 21'. Element 21' is more in the nature of a band and has hooks 34 at its terminals detachably engaging slots or openings 23' longer than those at 23. The connection of the hooks 34 with the plate, here designated 26', is separable or detachable in the absence of the insulating body 10, since the hooks 34 detachably engage openings 23'. Element 21' thus functions similarly to the elements 21.

15 In Figure 6, a further modified form is shown wherein the body 10' is constructed approximately like that at 10. Embedded therein is a metallic plate 20" functioning like that at 20 and 20' and having metallic elements 21" like those at 20 21 and 21'. In this instance, in lieu of a detachable screw, or fastening element, a fastening element 35 is formed integrally in the plate 20" and is shown specifically in the form of a screw engaged with a board 36 of a wooden building, 25 or the equivalent.

30 In the use of the invention, in all of its forms, the telephone wires, or the equivalent, pass through an opening 17 and they are connected, guided, anchored to, or dead end connected in any of the grooves 18, and the body of the insulator may be arranged at any desired angle and the wires wound around the grooves of one or more of the spools, as conditions warrant. Should the insulating material of the body fracture or break away, the telephone or other wires 35 will be held against displacement by the metallic elements 21, 21' or 21", which may later be detached at their junction with the plates 20, 20' or 20", incidental to the replacement of the insulator or insulator bracket.

40 It will be realized that the metallic parts 20 and 21, 20' and 21', and 20" and 21" function dually in that they greatly reinforce the body or insulation, and, also, retain the telephone or other wires, should the insulating body fracture.

45 Various changes may be resorted to, provided they fall within the spirit and scope of the invention, as described by the appended claims.

What is claimed is:

50 1. An insulator structure of the class described

having a body of insulation for engagement by wiring and having an opening through which the wiring passes, said body having an attaching surface marginally thereof and a bore extending from said opening to said surface, a plate disposed across said bore, a device embedded in the body in mechanical union with and extending from opposite end portions of said plate and jointly therewith surrounding said opening, said plate continuously around its margin being embedded in said body, said plate and device serving to reinforce the body and functioning to retain the wiring should the body fracture, and attaching means at said bore extending from the plate. 15

2. An insulator structure of the class described having a body of insulation for engagement by wiring and having an opening through which the wiring passes, said body having an attaching surface marginally thereof and a bore extending from said opening to said surface, a plate disposed across said bore, a device embedded in the body in mechanical union with and extending from opposite end portions of said plate and jointly therewith surrounding said opening, said plate continuously around its margin being embedded in said body, said plate and device serving to reinforce the body and functioning to retain the wiring should the body fracture, attaching means at said bore extending through an opening in said plate, fastenings for the attaching means on opposite sides of said plate in said bore, said bore initially providing clearance to enable application of said fastenings to said attaching means. 35

3. An insulator structure according to claim 1 having disaligned spools about said opening, said spools having ribs and intervening wire-engaging grooves, certain ribs of different spools being terminally integral with each other. 40

4. An insulator structure according to claim 1 having said plate provided with openings adjacent each end portion, said device at opposite ends being mechanically anchored in said latter mentioned openings. 45

5. An insulator structure according to claim 1 having said plate provided with openings, said device being a band having hooks at its terminals engaging the last mentioned openings.

LORY B. STEWART. 50
